Henry Müller

United States Patent Office.

HENRY MULLER, OF NORTH CAMBRIDGE, MASSACHUSETTS.

Letters Patent No. 78,815, dated June 9, 1868.

IMPROVED MACHINE FOR STUFFING LEATHER.

The Schedule referred to in these Letters Patent and making part of the same.

TO ALL WHOM IT MAY CONCERN:

Be it known that I, HENRY MULLER, of North Cambridge, in the county of Middlesex, and State of Massachusetts, have invented an Improvement in Stuffing Leather; and I do hereby declare that the following, taken in connection with the drawings which accompany and form part of this specification, is a description of my invention sufficient to enable those skilled in the art to practise it.

In the process of stuffing leather, which is the act of working it with oil, to cause the oil to penetrate the leather to make it soft and flexible, close rotary wheels, drums, or cylinders have been employed, into which the greasy matter and the leather have been introduced.

Heat is then applied by steam-pipes, and otherwise, and, by rotating the wheel, the leather is lifted and let fall, and is thus turned, worked, and beaten till it absorbs the oil or other suitable greasy matter.

After the leather is warmed, the action of the wheel generates so much heat that the temperature so generated added to the heat applied is apt to burn the leather, to retard the absorption of the oil, and to evaporate it; and it is to remedy these difficulties that is the object of my invention described herein.

In the practice of my invention I make use of a heated closed wheel or drum, such as has been employed heretofore, and when the wheel has been revolved sufficiently to uniformly warm up the leather to the desired temperature, I transfer the leather thus warm and covered with oil into a wheel, such as is shown in the drawing, half in section and half in elevation, and then, by rotating said wheel, finish the stuffing process without increasing the heat, as the heat generated by the movement about equals the heat lost by radiation and conduction.

The wheel shown in the drawing has a close circumference, *a*, and a close skirting, *b*, adjoining the circumference, to prevent loss of oil as the leather is moved by the rotations of the wheel. But the sides or ends of the drum or wheel are open, to permit a free circulation of air, as shown, instead of closed, as heretofore, and no heat is applied to the wheel; hence, as it rotates, the air moves freely through the wheel, taking off the heat generated in the movement of the leather.

The open sides of the wheel may be made as shown, by using arms or spokes, or the construction may be varied, so long as air is freely admitted to circulate through the wheel.

The door or trap through which the leather is entered and withdrawn is shown at *c*, and bars, *d*, are made to extend across the wheel, being made fast to the skirting, so as to give projections to increase the rapidity of the beating and softening of the leather as it falls when carried up by the rotations of the wheel.

I claim, in the process of stuffing leather, the employment, subsequent to treating the leather with oil in a warm close drum or wheel, of a wheel or drum, so constructed as to admit free access of the air to the leather, substantially as and for the purpose described.

Also, the wheel, with the close circumference *a*, and skirting *b*, the door *c*, and cross-bars *d*, when made open at the heads or sides of the wheel or drum, as and for the purpose described.

HENRY MULLER.
